Attorney

UNITED STATES PATENT OFFICE.

FRANK ADAMS, OF MILWAUKEE, WISCONSIN.

BOOK-SEWING BENCH.

SPECIFICATION forming part of Letters Patent No. 514,691, dated February 13, 1894.

Application filed July 5, 1893. Serial No. 479,550. (No model.)

To all whom it may concern:

Be it known that I, FRANK ADAMS, a citizen of the United States, residing at Milwaukee, county of Milwaukee, State of Wisconsin, have invented a certain new and useful Improvement in Book-Sewing Benches; and I declare the following to be a full, clear, and exact description of the invention, such as will enable others skilled in the art to which it pertains to make and use the same, reference being had to the accompanying drawings, which form a part of this specification.

My invention relates to new and useful improvements in the construction of book sewing benches, and my said invention consists in the matters hereinafter described and more particularly pointed out in the appended claims.

In the accompanying drawings: Figure 1.— is a front elevation of my improved book sewing bench showing a number of book signatures upon the same. Fig. 2.—is a broken vertical sectional view of the same, taken on line 2—2 of Fig. 1. Fig. 3.—is a detail view 25 of one of the parts.

Referring by letter to said drawings, A designates a suitable table or base upon which the signatures are placed, as they are stitched or sewed together to form a book. Adjacent to the forward corners of the table or base are provided vertical standards B B which are arranged to be adjusted vertically within suitable slots or openings in the corners of the table. The upper ends of these standards are conveniently screw-threaded as shown at a a for the reception of nuts C C and a transverse bar D is provided at its opposite ends with suitable apertured enlargements d d arranged to fit over the upper ends of the standards in the manner shown, and to rest upon and be supported by the nuts C C in an obvious manner. It follows from this construction that by a rotation of the nuts C C the elevation of the transverse bar D may be varied as desired.

At a convenient point upon each of the vertical posts B is provided a hinge E the posts being separated at this point into two sections and the hinge permitting said post to be folded over into the position indicated in Fig. 2 by the dotted lines.

Upon the rear face of each post, opposite

to the hinge, is provided a snap hook or catch e which is secured to the upper section of the post, and arranged to engage with a corresponding hook, e' upon the lower section of the post, so as to normally hold the upper and lower sections in line with each other, but said hooks are so arranged as to permit the upper section of the post to be folded or bent over as shown by the dotted lines in Fig. 2, by a smart pull upon the upper end of the post or the transverse bar D engaged therewith.

Upon one side of each post, is provided a suitable rack bar F arranged to engage with a pinion F' which is mounted upon a rotary transverse shaft f, in the manner shown in Fig. 2, two of these pinions being provided for engagement with the two posts and the shaft upon which they are mounted being arranged to extend to the outside of the table or base and terminating in suitable operating handles f' f'.

Adjacent to each one of the pinions F' is provided a spring or pawl G, which engages at its free end with the teeth of the pinion, and serves as a ratchet to permit the rotation of said pinion in one direction only, and a second transverse shaft or rod g is arranged to extend beneath the table in contact with the upper faces of the two springs G G, said shaft or rod being provided with flattened or eccentric portions or faces, at the points where it engages with said springs as shown more particularly in Fig. 2. By a rotation of said shaft or rod, g, the springs may be pressed out of engagement with the teeth of said pinions in an obvious manner, so as to free said pinions and permit their rotation in either direction as may be desired, and upon the outer end of said shaft or rod, is provided a suitable handle or knob, g', by means of which said shaft or rod may be readily turned.

Beneath the table A, and conveniently secured to a shaft or rod h, are a suitable number of short straps, provided at their free ends with buckles H H for engagement with the usual straps I I which are arranged in the backs of books and to which the signatures are sewed. A desired number of short straps J J are secured to the transverse bar D in the manner shown and provided at their lower ends with suitable buckles j j for engagement

with the upper end of the straps I I, these straps J J being conveniently formed from elastic webbing so as to give slightly and at the same time preserve a uniform tension 5 upon the straps I I.

At the front edge of the table is provided a transverse strip K of elastic material, which is arranged to normally bear against the front edge of the table and a suitable adjusting 10 screw k is threaded through said elastic strip K and arranged to bear against the front face of the table so that by an adjustment of the screw the elastic strip K may be sprung outward away from the edge of the table or permitted to bear against the edge of the table 15 as may be desired. In practice when the straps I I are to be placed in position, the adjusting screw k is turned so as to spring the elastic strip K away from the edge of the table and said straps are then slipped through 20 the space between said elastic strip and the table and their lower ends engaged with the buckles H H upon the straps beneath the table. The upper ends of said straps I I are 25 then engaged with the buckles j j upon the lower ends of the straps J J in the manner illustrated in the drawings, when the strip K may be permitted to spring back against the edge of the table so as to grasp the lower ends 30 of the straps I I in an obvious manner.

In commencing a book, the vertical posts are first adjusted so that the hinges E E come to the level of the top of the table. The first signature of the book is then placed upon the 35 table and stitched to the straps in the ordinary manner, the thread L being passed around each of the straps I I and through the signature of the book. The next signature is then placed in position upon the first signature and the vertical posts are adjusted by 40 means of the handles f' f' in the manner before described so as to elevate the hinges E E to the same level as the line of division between the first and second signatures of the book. Then the operator passes the thread 45 or twine alternately around the straps I I and from signature to signature of the book, so as to not only secure the individual signatures to the straps, but to secure the sections to 50 each other independently of the straps. It is necessary in order that the stitching may be carried from one signature to another that the two signatures be open at their folds for the passage of the thread therethrough, and 55 at the times when it is desired to stitch from one signature to another, the operator by a pull upon the transverse bar D turns the upper sections of the vertical posts into a horizontal position, the straps I I also bending in 60 the same horizontal plane with the hinges E E, so as to permit the two signatures of the book to be opened out horizontally in an obvious manner. As soon as the thread is passed from one signature to another and it is 65 desired to again pass the thread around one of the straps I the operator throws the transverse bar and the hinged upper sections of the

standards or posts back into their normal positions when the thread may be readily passed around the strap in the ordinary manner. In 70 this manner the signatures are placed one upon another and each succeeding signature sewed not only to the straps but to the next preceding signature until the required number of signatures have been secured together, 75 and as rapidly as the signatures are placed upon the series, the standards B B are elevated so as to bring the hinges E E into the same horizontal plane with the line of separation between the uppermost signature and 80 the signature next below it. As the posts are adjusted vertically upward, the nuts C C are turned downward upon the upper ends a a of said posts, so as to preserve the same elevation of the transverse bar D above the upper 85 surface of the table.

In the particular form illustrated in the drawings, I have shown a series of straps or strips of webbing I I at the back of the book which straps are usually applied to the backs 90 of very heavy books such as large ledgers and books of account which are destined to undergo severe usage, but if desired cords or twines may be substituted for the straps for smaller books, in the ordinary manner in 95 which case the method of stitching or sewing the signatures to the twines and to each other will be precisely the same as that hereinbefore described.

In the ordinary methods of book sewing, 100 the straps at the back of the series of signatures are usually tacked or nailed to the under side of sewing bench, and are passed around the transverse bar at their upper ends and stitched together, while by my improvement, all of the labor and time required for thus attaching the straps, is done away with, and it is only necessary to buckle the upper and lower ends of said straps, to the straps on the transverse bar D, and the rod h, beneath 110 the bench.

The straps J J, and the rod h with the straps attached thereto, may be applied to any of the ordinary forms of sewing benches if desired. 115

Having thus described my invention, what I claim as new, and desire to secure by Letters Patent of the United States, is—

1. A book-sewing bench comprising a table vertical standards adjustably supported adjacent to the front edge of the table, a transverse bar extending from the upper ends of said standards, a plurality of connections for vertical straps or cords upon said transverse bar, and means upon the table for engagement with the lower ends of said straps or cords, said standards being composed of upper and lower sections hinged together substantially as shown and described. 12c

2. A book-sewing bench comprising a table, 130 vertically disposed standards, movably supported adjacent to the front edge of the table, said standards consisting of upper and lower sections hinged together, spring catches or

hooks, for normally holding the sections of said posts in line with each other, means for vertically adjusting said posts, a transverse bar extending between the upper ends of said posts and vertically adjustable thereon, and means for engagement of the upper ends of a series of straps or cords with said transverse bar, and of the lower ends of said straps or cords, with the under side of the table, substantially as described.

3. A book sewing bench comprising a table, vertical standards adjustably supported adjacent to the front edge of said table, and consisting of upper and lower sections hinged together, hooks or catches for normally holding said upper and lower sections in line with each other, means upon the table for vertically adjusting said standards, suitable nuts having screw threaded engagement with the upper sections of said standards, a transverse bar arranged to rest upon said nuts, and provided with means for detachable engagement with the upper ends of a series of straps or cords, a clamp upon the front edge of the table for engagement with the lower portions of said straps or cords, and a transverse rod or bar below the forward edge of said table provided with a series of attaching devices for engage-

ment with the lower ends of said straps or cords, substantially as described.

4. A book sewing bench comprising a table, vertical standards adjustably supported adjacent to the front edge of said table, and consisting of upper and lower sections hinged together, hooks or catches for normally holding said upper and lower sections in line with each other, rack teeth upon the lower sections of said standards, a transverse shaft provided with an operating handle, and carrying suitable pinions operatively engaged with said rack teeth for producing a vertical adjustment of said standards, nuts having screw threaded engagement with the upper sections of said standards, a transverse bar arranged to rest upon said nuts, and provided with means for detachable engagement with the upper ends of a series of straps or cords, and means upon the forward edge of the table for engagement with the lower ends of said straps or cords substantially as described.

In testimony whereof I sign this specification in the presence of two witnesses.

FRANK ADAMS.
